Patented Dec. 12, 1961

191,899

VACUUM CLEANER NOZZLE

Robert J. McKnight, Springfield, Ohio, assignor to
Orly Musgrave, Springfield, Ohio

Filed Sept. 24, 1959, Ser. No. 57,662

Term of patent 7 years

(Cl. D9—2)

FIG.-1

FIG.-2

FIG.-3

FIG.-4

FIGURE 1 is a top plan view of a vacuum cleaner nozzle, showing my new design;

FIGURE 2 is a front elevational view;

FIGURE 3 is a bottom perspective view thereof; and

FIGURE 4 is a bottom plan view thereof.

I claim:

The ornamental design for a vacuum cleaner nozzle, substantially as shown.
